UNITED STATES PATENT OFFICE

2,201,036

SEESAW

Edwin J. Guerrier, New Orleans, La.

Application February 13, 1939, Serial No. 256,162

1 Claim. (Cl. 272—55)

This invention relates to seesaws. It is particularly directed to a seesaw which may be used and operated by one child.

An object of this invention is to provide a seesaw of the character described, provided with adjustable means to accommodate the seesaw to children of different weight.

A further object of this invention is to provide a strong, rugged and durable seesaw of the character described, which shall be easy to adjust and operate, relatively inexpensive to manufacture, attractive in appearance, and withal practical and efficient to a high degree in use.

Other objects of this invention will in part be obvious and in part hereinafter pointed out.

The invention accordingly consists in the features of construction, combinations of elements, and arrangement of parts which will exemplified in the construction hereinafter described, and of which the scope of application will be indicated in the following claim.

In the accompanying drawing, in which is shown one of the various possible illustrative embodiments of this invention:

Fig. 1 is a front elevational view of a seesaw, embodying the invention, with parts broken away and in cross-section;

Fig. 2 is a top plan view thereof;

Fig. 3 is a front elevational view thereof; and Fig. 4 is a cross-sectional view taken on line 4—4 of Fig. 1.

Referring now in detail to the drawing, 10 designates a seesaw embodying the invention, which may be easily operated by a child, and which will provide healthful and muscle building exercise for the child.

The seesaw 10 has a base comprising a pair of parallel, similar, front and rear base boards 11 and 12, the upper surfaces whereof are formed with central, aligned grooves 11a and 12a to receive the front and rear ends of an elongated member 13, fixed to said boards by screws or in any other suitable manner.

Fixed to the member 13 and located closer to the front of said member than to the rear thereof, is an upstanding post 15 formed with a groove 16 at its upper end, to provide a pair of parallel walls 17. The walls 17 are formed with aligned openings 18 to receive a horizontal pivot pin 19 traversing the groove 16. On the pivot pin 19 is a metal sleeve or bushing 19, for the purpose hereinafter appearing.

Pivoted to the pivot pin 19, in a manner hereinafter appearing, is an elongated board 22. The board 22 fits within the groove 16, and fixed to

the underside of said board is a channel shaped member 23, rotatably receiving the sleeve or bushing 19. The portion of the board 22, located rearward of the fulcrum 19, is preferably of greater length, than the portion of said board which is located forwardly of said fulcrum.

Attached to the rear portion of the board 22 is a seat 25 of any suitable construction. Fixed to the board 22, forwardly of the seat 25, and extending upwardly therefrom, is a handle 26 adapted to be grasped by a child sitting on the seat 25. The front end of the board 22 is connected to the front end of member 13 by a spring 30, in the manner hereinafter appearing, to aid in raising the board 22 for lifting a child sitting on said seat 25 when the child pushes himself up.

In order to accommodate children of different weight, there is attached to the forward end of member 13, a bracket 31 having a plurality of spaced humps 33. There is also attached to the underside of the forward end of the board 22, a bracket 34, similar to the bracket 31 and aligned therewith, and likewise provided with a plurality of spaced humps 35.

The spring 30 is preferably in the form of a coil tension spring, having hooks 37 at its outer ends to engage aligned pairs of humps 33, 35.

It will now be understood that spring 30 may be shifted closer or further away from the fulcrum 19, to take care of children of different weight.

Means is furthermore provided to yieldingly brake the upward movement of a child on the seat 25. To this end, there is fixed to the board 13, a bracket 40. Said bracket 40 may be attached at one end to the upper end of the post 15 to reinforce the post. The bracket 40 is provided with an aperture 41 to receive a U-shaped wire member 42, having upwardly extending arms 43 provided with downwardly hooked portions 44 at their upper ends. Received on member 42 is a coil compression spring 45.

Fixed to the underside of the board 22 is an eyelet 47, and connected to the eyelet 47 is an inverted U-shaped member 48, similar to member 42, and having arms 49 extending downwardly through the coil 45, and provided at their lower ends with upwardly hooked portions 50. The coil compression spring 45 is interposed between the hooks 50 and the hooks 44.

It will now be understood that as the spring 30 pulls the front of the board 22 downwardly, the rear end thereof is moved upwardly to compress the spring 45. As the seat swings up, the compression on the coil spring 45 increases to brake the upward swing. The coil spring 30 is

preferably heavier than the spring 45, so that a child sitting on the seat 25 will be pushed upwardly.

It will be noted that the spring 45 and the U-shaped members 42, 48 are directly below the board 22, so as not to be in the way of the legs of the child using the seesaw.

The operation of the device will now be explained:

10 The child sitting on the seesaw grasps the handles 26 for support. The spring 30 normally counterbalances the weight of the child. However, the weight of the child is sufficient to bring him down for rotating the board 22 in a clockwise direction and tensioning spring 30.

When the child is down, his feet reach the ground and he pushes himself up slightly. The upward push by the child's legs, together with the pull of the spring 30, causes the board 22 to move in a counterclockwise direction. This rotation is braked by the spring 45, and when the upward push by the child is spent, the compression of the spring 45, coupled with the weight of the child, causes the child to come down for tensioning the spring 30 to again aid in swinging the child up.

It will thus be seen that there is provided a device in which the several objects of this invention are achieved, and which is well adapted to meet the conditions of practical use.

30 As various possible embodiments might be made of the above invention, and as various changes might be made in the embodiment above set forth, it is to be understood that all matter herein set forth or shown in the accompanying drawing is

to be interpreted as illustrative and not in a limiting sense.

Having thus described my invention, I claim as new and desire to secure by Letters Patent:

5 In a seesaw, a base, a post fixed thereto and extending upwardly therefrom, a member pivoted meditately the ends thereof to the upper end of said post, a bracket attached to the upper side of said base, forwardly of the post, and provided with a plurality of humped portions, a similar, 10 symmetrically disposed bracket attached to the underside of said pivoted member, and likewise provided with a plurality of humps, a spring interconnecting said brackets and having hooked portions at the ends thereof selectively engaging said humps, a seat on the rear end of said pivoted member, a handle fixed to said pivoted member forwardly of the seat and extending upwardly therefrom, a bracket interconnecting the portion of the base rearwardly of the post, with the upper 15 end of said post, said bracket being formed with an opening, a U-shaped member engaging said opening and having upwardly extending parallel arms formed with downwardly hooked edge portions at their upper ends, an eyelet fixed to the 20 underside of said pivoted member, rearwardly of said post, an inverted U-shaped member on said eyelet and having downwardly extending arms provided at their lower ends with upwardly hooked portions, and a coil compression spring receiving 25 said U-shaped members, and interposed between the hooked shaped portions of the arms of one U-shaped member and the hooked portions of the arms of the other U-shaped member.

EDWIN J. GUERRIER. 35
